UNITED STATES PATENT OFFICE.

FRANZ XAVER KOMAREK, OF VIENNA, AUSTRIA-HUNGARY.

STEAM-BOILER.

SPECIFICATION forming part of Letters Patent No. 742,335, dated October 27, 1903.

Application filed May 24, 1902. Serial No. 108,861. (No model.)

To all whom it may concern:

Be it known that I, FRANZ XAVER KOMAREK, a subject of the Emperor of Austria-Hungary, residing at Vienna, Austria-Hungary, have invented new and useful Improvements in Steam-Boilers, of which the following is a specification.

The present invention has reference to improvements in steam-boilers, and relates more especially to sectional steam-boilers for high pressure with superheater, especially for use in automobiles and the like; and the object of the invention is to provide a boiler of the type indicated which is of great efficiency, yet shows relatively small dimensions.

In order to make my invention more readily understood, I will describe it with reference to the accompanying sheets of drawings, of which—

20 Figure 1 represents a vertical sectional elevation of my improved boiler on line 1 1 of Fig. 3. Fig. 2 is a vertical sectional elevation through Fig. 1. Fig. 3 is a horizontal sectional elevation on line 2 2 of Fig. 2, and 25 Fig. 4 is a horizontal section through Fig. 2 on line 3 3.

The boiler essentially consists of one or more coils of pipe A, arranged as tubular bodies concentrically within one another, the outer 30 coil forming the wall of the fire-box of the water and steam collector B and of the superheater C. The coils A are made up of separate sections and are formed of thick-walled material with relatively small diameter.

35 Each section communicates directly by its two coil ends with the water and steam collector B. Instead of using only one such collector two or more may be made use of. By this arrangement of directly-communicating 40 sections there is assured a regular active circulation in each section. A "boiling empty" of the coils therefore is excluded, and with always sufficient supply of water the generation of steam is enhanced. In the 45 upper section or sections the steam at first is dried and then highly superheated to such an extent that besides obtaining an extremely

high potential of force the escaping steam of the motor will be colorless. Each section consists of but one length of pipe, so that no 50 joints occur which could come in contact with the fire.

The collector B and the coils are surrounded by a casing G. Thus the collector is to a great extent kept heated; but the joints between the several sections of coil and the collector are isolated from the direct effects of the heat by the fact that the coils are separated from the collector and said joints by an internal casing H, surrounding the coils. 55 At the bottom the outer tubular body of coils is abruptly extended outwardly relatively to that portion thereof which is above it, so as to form a stoking-aperture I. J is a hinged door on casing G, covering said stoking-aperture. 60

What I claim, and desire to secure by Letters Patent, is—

1. The combination of a tubular body consisting of a coil or coils, a water-supply pipe 70 communicating with said body, a steam-dispensing pipe also communicating with said body, and a fuel-support disposed under said body, the coils at the bottom portion of said body being extended abruptly laterally to 75 form a stoking-aperture, substantially as described.

2. The combination of a tubular boiler comprising a series of coils, a water-supply pipe and a steam-dispensing pipe communicating with said boiler, and a fuel-support disposed under and close to said boiler, some of said coils being extended abruptly laterally to form a stoking-aperture and the coils from said aperture down to the grate being 85 combined with the grate to form a fuel-receiving space, substantially as described.

In witness whereof I have hereunto set my hand in presence of two witnesses.

FRANZ XAVER KOMAREK.
